REVERSIBLE DOUBLE BRUSH

Richard Fischer, Frankfurt am Main, Germany, assignor
to Coronet-Werke Heinrich Schlerf GmbH

Filed June 22, 1971, Ser. No. 155,679

Term of patent 14 years

Int. Cl. D4—02

U.S. Cl. D4—13

FIG. 1 is a perspective view of a reversible double brush according to my invention;

FIG. 2 is a side elevation, and

FIG. 3 is an end elevation.

I claim:

The ornamental design for a reversible double brush, substantially as shown and described.
